UNITED STATES PATENT OFFICE.

LEWIS LEIGH, OF SEYMOUR, CONNECTICUT.

IMPROVEMENT IN LUBRICATORS.

Specification forming part of Letters Patent No. 44,005, dated August 30, 1864.

To all whom it may concern:

Be it known that I, LEWIS LEIGH, of Seymour, in the county of New Haven and State of Connecticut, have invented, made, and applied to use a certain Improvement in Lubricators for Spindles, &c.; and I do hereby declare the following to be a full, clear, and exact description of the same, reference being had to the annexed drawings, making part of this specification, wherein—

Figure 1 is a vertical section of my improved lubricator as applied to a spindle that passes through a globular bolster, and Fig. 2 is a similar view of my lubricator as applied to a vertical shaft or rod passing through an ordinary bearing.

Similar marks of reference denote the same parts.

Great difficulty has heretofore been experienced in lubricating the vertical spindles in spinning machinery, vertical shafts, and sliding rods, in consequence of the oil running down through the bearing or bolster and the parts speedily becoming dry, causing wear and friction; and with spindles in spinning-frames the velocity is so great that the centrifugal force prevents the oil from passing down through the bolster, rendering it necessary to stop the machine, sometimes twice a day, for the oil to pass down into the bolster.

The nature of my said invention consists in an oil-vessel provided with a horizontal or nearly horizontal conductor containing a capillary wick, in combination with a pipe-shaped globular bolster, so that the end of said conductor retains said bolster in its place, and the wick comes in contact with the spindle, shaft, or rod to be oiled about the middle of the bearing, and supplies thereto the lubricating material in a gradual manner, only the amount necessary for the same being supplied from time to time. Thereby waste of oil by it running down the spindle or shaft is avoided, and but little attention is required to such spindles

or shafts, because the oil-vessel only requires to be occasionally replenished.

In the drawings, *a* is a journal box or bearing of any suitable kind, taking the lower end of the shaft *b*, and *c* is a bolster formed as a pipe surrounding *b*, and with a globular collar setting within the bearing *d*. This globular and pipe bolster, however, is not my invention.

e is a reservoir or oil-vessel, of suitable size, at the top of which is a supply-hole, *b*, and from the side thereof extends an oil-conductor, *g*, running horizontally or nearly horizontally and terminating near the side of the shaft, spindle, or rod to be oiled. This conductor is formed with a screw-thread around it, taking a thread in *d*, whereby the lubricator is attached. This conductor *g* contains a cotton or other capillary wick, which prevents the oil escaping too quickly, and remains sufficiently saturated for lubricating the vertical spindle or shaft until the oil is exhausted from the vessel *e*.

The lubricator shown in Fig. 2 is the same as that in Fig. 1, but the shaft or spindle *b* is represented in Fig. 2 without the bolster. The operation of lubricating will be the same in both instances, but in Fig. 1 the end of the conductor answers the additional purpose of preventing the spindle-bolster from turning.

I do not claim, broadly, a lubricator containing a capillary wick; but

What I claim, and desire to secure by Letters Patent, is—

The combination of the said lubricator with the pipe-shaped globular bolster *c*, for the purposes and as specified.

In witness whereof I have hereunto set my signature this 27th day of November, A. D. 1863.

LEWIS LEIGH.
